Patented Nov. 22, 1921.

UNITED STATES PATENT OFFICE.

LESLIE C. MILNER, OF INDIANAPOLIS, INDIANA.

AUTOMOBILE-HEATER.

1,397,648.

Specification of Letters Patent.

Patented Nov. 22, 1921.

Application filed December 13, 1920. Serial No. 420,396.

To all whom it may concern:

Be it known that I, LESLIE C. MILNER, a citizen of the United States, residing at Indianapolis, in the county of Marion and State of Indiana, have invented new and useful Improvements in Automobile-Heaters, of which the following is a specification.

The object of this invention is to collect the heat radiating from the exhaust manifold of an automobile and discharge it by the advance movement of the car and drive of the radiator fan back into the car to warm the passengers.

A further object is to provide means for installation and assembly in many cars of the present popular design without cutting passageways especially for it, and to provide easy, quick, and simple means for installing the device in cars already in use or made.

I accomplish the above, and other objects which will hereinafter appear, by the mechanism illustrated in the accompanying drawing, in which—

Figure 1 is a view in side elevation of my invention and the associated parts of an automobile in which it is shown assembled. Fig. 2 is a top plan view of the invention detached from the car. Fig. 3 is an end elevation looking toward the rear of the car. Figs. 4 and 5 are vertical sections looking in respective opposite directions from the dotted line 4—4, 5—5 of Fig. 2.

Like characters of reference indicate like parts in the several views of the drawing.

In the drawing, 6 are the engine cylinders, 7 the exhaust manifold, 8 the fan which draws atmospheric air in through the radiator (not shown) and discharges it rearwardly longitudinally of the exhaust manifold, 9 is the dash, 10 the coil box supported by the dash and 11 is the floor of the body of the car. In some of the most popular cars the dash extends over the adjacent end of the engine and a dished metal segment 12 completes the closure between the interior of the car body and the indent in it for the engine. This segment has a flange with holes for screws by which it is easily removed, and when removed it provides the necessary opening into the body of the car from in front where the manifold is located. By cutting away a portion of the segment plate 12 in the vertical plane of the exhaust manifold there is sufficient room for the passage

into the car of a hood conveying heat radiated from the exhaust manifold. This hood is in two transversely divided parts 13 and 14. The part 13 is open at the bottom for its entire length to receive the manifold by being pushed down over it. Its lower edges when it is in place are substantially horizontal, but the roof which is semicircular in cross section slopes from the end next the fan upwardly toward plate 12 in order to pass into the car body and to help the air-flow. The sides of 13 are substantially parallel, the one next to the engine being somewhat shorter than the outer one because of the glands from the engine cylinders to the exhaust manifold upon which this side rests. The lower edge of the outer side of the part 13 is turned in to form a stiffening flange 15 and riveted to the inner wall of this side are the depending ears 16, 16, which are clamped under the adjacent members 17 of the engine. The end of the part 13 is flared outwardly at 18 to form a funnel the better to collect air driven back by the fan 8, and rearwardly sloping fins or baffle plates 18' are provided in the upper portions of the part 13 to increase the distance of travel of the air in contact with the hot manifold and to more completely mix the hot and cold air.

The part 14 of the hood is high enough to receive the expanded rear end of 13 and form a dead air pocket over the downwardly bent discharge end of the exhaust manifold, and its tapering walls are closed at the lower as well as lateral and top portions to form a dead-air pocket and to direct the heated current of air to its discharge at its rear through the segment plate 12. The member 13 extends rearwardly of and below the exhaust manifold 7 into contact with the downwardly bent discharge end of the latter to increase the size of the dead air pocket. The end of part 13 is made oblique at 19' to correspond with and contact the sloping bottom of part 14 as clearly shown in Fig. 5.

A receptacle 19, here shown as cylindrical but which may be suitably formed in other shapes is fastened by suitable means, here shown as screws 20, 20, to the segment plate 12, and may be removably secured as shown, to allow of disconnection in shipping, and the like. The wall of the receptacle next to the plate 12 has an opening through which the small end of part 14 discharges into the interior of the receptacle. A joint is preferably made here by forming a series

of tongues 21 from the material of the receptacle wall that would be otherwise cut away, and bending them out and inside of the part 14 where their contact with the 5 walls of the latter makes the joint more secure. This joint may be made still more secure by soldering on the outside. The receptacle is long enough to afford ample distribution of the hot air inside the car and 10 for the discharge of the air a horizontal series of holes is provided which is closed by a sliding damper-plate 23, having registering holes that may be brought opposite the holes in the receptacle wall when it is 15 desired to discharge hot air into the car.

In practice I have found it more convenient to the user to furnish the device with segment plate 12 already cut and attached so all he will have to do is to remove the 20 original plate that comes with the car and replace it with the new one with my device fitted and attached to it. This is done with the part 13 detached after which the assembly is completed by slipping part 13 into 25 place and clamping the ears 16 under arms 17.

The fins 18' may be omitted in most cases in climates where great severity of weather does not require all possible obtainable heat 30 in the car.

In practice the air in the dead air pocket adjacent the downwardly bent discharge end of the exhaust manifold becomes superheated instead of rushing past too quickly 35 to become heated as would otherwise be the case, and the air current following the sloping top of the hood drags part of the superheated air of the pocket with it and discharges it into the receptacle 19.

Having thus fully described my invention what I claim as new and wish to secure by Letters Patent of the United States, is—

1. In an auto-car, the combination with a 40 passenger body and an internal combustion engine having an exhaust manifold, said engine and manifold being located outside of the body, of a heat distributing receptacle located within the body, damper means in the wall of the receptacle, and a hood in 45 two separable parts one of which discharges into the heat distributing receptacle and extends to the adjacent end of the manifold and the other part of which extends for-

wardly from the first part and envelops the top and sides of the manifold.

2. In an auto-car, the combination with a 55 passenger body, an internal combustion engine in a compartment in front of the body separated therefrom by a partition, and a hood discharging heat from the engine compartment into the body, of a plate forming part of said partition between the body and said engine compartment through which plate the hood passes and to which plate the hood is fastened.

3. In an auto-car, the combination of a 60 body, an internal combustion engine in a compartment in front of the body, a plate closure between the body and engine compartment, a heat distributing receptacle 65 within the body removably secured to the plate, and a hood discharging the heated air from the engine compartment into the receptacle.

4. In an auto-car the combination of a 70 body, an internal combustion engine in a compartment in front of the body, a plate closure between the body and engine compartment, a heat distributing receptacle 75 within the body removably secured to the plate, and a hood discharging the heated air from the engine compartment into the receptacle, said hood being in a plurality of parts connected by telescopic joints.

5. In a heater for automobiles, the combination with a body of an internal combustion engine having an exhaust manifold, a 80 heat distributing receptacle in said body, and a hood in two parts one of which parts is fastened to the distributing receptacle and the 85 other of which parts is connected with the first part and also surrounds the top and sides of the exhaust manifold, said hood being separable into its parts adjacent that end of the exhaust manifold which is nearest the receptacle.

6. In an auto-car, a body, an engine in a compartment in front of the body, a hood conveying heat from the engine to the body, and a removable plate-closure between the 90 body and engine compartment having an opening for the passage of the hood.

Signed at Indianapolis, Indiana, this the 9th day of December, 1920.

LESLIE C. MILNER.
